UNITED STATES PATENT OFFICE.

JAMES M. GAGAN, OF CHICAGO, ILLINOIS.

DESIGN FOR A CASING FOR COUNTERBALANCE-SPRINGS.

SPECIFICATION forming part of Design No. 30,238, dated February 21, 1898.

Application filed November 18, 1898. Serial No. 696,846. Term of patent 3½ years.

To all whom it may concern:

Be it known that I, JAMES M. GAGAN, a citizen of the United States, and a resident of Chicago, in the county of Cook and State of Illinois, have invented and produced a new, 5 useful, and original Design for a Casing for Counterbalance-Springs, of which the following is a specification.

In the accompanying drawings, Figure 1 is 10 a side view of a casing of my design. Fig. 2 is an end view thereof.

A casing of my design comprises a tubular shell or barrel A, on one end of which is a head A'. Formed in the end of the head A' is a 15 hole or opening a, which is smaller than the bore of the tube or barrel A. Said head will thus form a shoulder projecting inwardly from

the inner surface of said tube or barrel. The head A' is also provided with feet or flanges a', formed at the end of a lateral projection 20 a² thereon, and formed in the end of said projection a² between said feet or flanges a' is a recess or socket a³.

I claim—

The design for the casing of a counterbalance-spring, substantially as shown and described. 25

In testimony that I claim the foregoing as my invention I have hereunto set my hand this 27th day of October, 1898.

JAMES M. GAGAN.

Witnesses:

THOMAS R. FERRIS,
B. KUMMEROW.
